WARM AIR FURNACE

Richard S. Dill, New Bern, N. C., assignor to
the Government of the United States, as repre-
sented by the Secretary of Commerce

Application January 9, 1943, Serial No. 471,828

4 Claims. (Cl. 126—110)

(Granted under the act of March 3, 1883, as
amended April 30, 1928; 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention relates to warm air heating furnaces and has for its object to provide an arrangement for utilizing the heat from a furnace to furnish mechanical power for increasing the air flow to the furnace.

With this object in view, the invention consists of the combination of the return air duct to the furnace and a hot air engine so arranged in connection with the furnace that the engine is operated by the heat of the furnace and the power supplied is utilized to operate a blower for forcing air to the furnace to be heated therein and distributed through ducts to various parts of a house.

A further object of the invention is to utilize the mechanical power supplied by the hot air engine for any appropriate purpose, either separately or in connection with the blower.

With these objects in view, the invention consists of the arrangement of the hot air engine in connection with a hot air furnace and the return air duct thereof, and also in certain details of construction, all of which will first be fully described and afterwards specifically pointed out in the appended claims.

Referring to the accompanying drawing:

The figure is a diagrammatic view illustrating the invention.

In the application of my invention, I prefer to use a hot air engine of the Lehmann type. This Lehmann type of engine is fully described in the book entitled "Technical Thermodynamics," Vol. I, by Zeuner and in other references. It is well known to those skilled in the art, and as I lay no claim to originality to the construction of the engine per se, its details have not been illustrated in the drawing nor described in this specification.

Referring to the drawing by reference numerals:

1 indicates a warm air furnace of a conventional type. 2 indicates the warm air supply ducts leading from the furnace 1, and 3 indicates the return air duct leading to the furnace. Connecting the return air duct 3 to the heated air drum 4 of the furnace 1 near the bottom thereof is a blower of conventional form.

Connecting with the fire box 6 of the furnace

1 is the hot end 7 of the cylinder of the hot air engine 8, while the cold end 9 of the cylinder of the hot air engine is disposed within the return air duct 3, the said cold end 9 of the cylinder of the hot air engine 8 being provided with heat radiating fins 10 within the return air duct 3 so as to more effectually cool the cold end 9 of the engine cylinder by the down draft of cold air passing through the return air duct 3.

Driven by the hot air engine 8 is a pulley 12 and belt 14 leading to the pulley 13 of the blower 5.

Having thus described the several parts of the invention, its operation is as follows: The device being assembled as shown in the drawing, the heat from the fire box 6 of the furnace 1, heats the hot end 7 of the cylinder of the engine 8, which starts the engine in operation. By reason of the pulleys 12 and 13 and the belt 14, the blower 5 is actuated. This causes an increased circulation of cold air downwardly of the return air duct 3 and into the heating drum 4 of the furnace 1, which at the same time absorbs the heat from the cold end 9 of the cylinder of the hot air engine 8.

The advantages of this arrangement are at once apparent, as by it the usual electric motor employed to drive the blower is displaced, while the power supplied from the hot air engine for the same purpose adds nothing to the cost of operation. Additionally, the engine is self regulating, since a brisk fire in the furnace causes the engine to run faster, thus increasing the air flow when more heat is required, and a slower running and less air flow when the fire in the furnace is low.

It is also obvious that a fan or other accessories may be operated by the engine either separately or in connection with the blower 5.

Having thus described the operation of the invention, I do not wish to limit myself to the exact arrangement of the parts illustrated in the diagrammatic figure of the drawing, as such may be changed or modified, and I consider myself clearly entitled to all such changes and modifications as fall within the limit and scope of the appended claims.

I claim:

1. The combination with a warm air furnace having a fire box, warm air drum, air supply ducts leading from the warm air drum, a cold air return duct and a blower for supplying cold air to the warm air drum, of a hot air engine having the hot end of its cylinder connected to

the fire box of the furnace and the cold end of its cylinder disposed within the cold air return duct and in the path of circulation of cold air within the cold air return duct and means connecting the hot air engine with the said blower for driving the blower.

2. The combination with a warm air furnace having a fire box, warm air drum, an air supply duct leading from the warm air drum, and a cold air duct and a blower for supplying air to the warm air drum, of a hot air engine having the hot end of its cylinder connected to the fire box of the furnace and the cold end of its cylinder disposed within the cold air duct and means connecting the hot air engine with the said blower for driving the blower.

3. In a device for generating power for any appropriate purpose, the combination with a warm air furnace having a fire box, warm air drum, an

air supply duct leading from the warm air drum, and a cold air duct for supplying air to the warm air drum, of a hot air engine having the hot end of its cylinder connected to the fire box of the furnace and the cold end of its cylinder disposed within the cold air duct and in the path of circulation of cold air within the cold air duct.

4. In a device for generating power for any appropriate purpose, the combination with a warm air furnace having a fire box, warm air drum, an air supply duct leading from the warm air drum and a cold air duct for supplying air to the warm air drum, of a hot air engine having the hot end of its cylinder connected to the furnace and the cold end of its cylinder disposed within the cold air duct and in the path of circulation of the cold air within the cold air duct.

RICHARD S. DILL.
